LIFTING JACK

Millard B. Lucker, St. Joseph, Mich., assignor to
 Auto Specialties Manufacturing Company, St.
 Joseph, Mich., a corporation of Michigan

Application September 21, 1936, Serial No. 101,693

13 Claims. (Cl. 254—106)

This invention relates to lifting jacks, and more particularly to a jack of the friction collar type especially adapted for use with automotive vehicles and the like. The present invention is particularly adapted as an improvement over the type of jack disclosed in my prior filed application, Serial No. 74,969, filed April 17, 1936. It is to be understood, however, that in so far as certain aspects of my present invention are concerned, such aspects are adaptable to types of jack other than that disclosed in said pending application.

In jacks of the type disclosed in my prior application, it has been found that in certain instances, and particularly when the upstanding shaft or standard—which corresponded to standard 11 in my prior filed application—became somewhat rusty, the lifting collar or actuating clamp 21, when moved downwardly to the position shown in Figure 5 of said application, tended to stick to the upright 11 so that the springs 25 of said prior application were insufficient to slide the clamp back to normal position, or that shown in Figure 2 of said prior application. Therefore, one of the objects of my present invention is to provide a jack of the type shown in my prior application, wherein positive means is provided for returning the actuating or lifting clamp to its upper position, whereby to eliminate any possibility of the same sticking in the lowermost position.

Another object of my invention resides in providing a jack of the foregoing and other types wherein the manually operable member for operating the actuating clamp 21 is provided with means for not only positively moving the actuating clamp downwardly relative to the stationary standard, but is also provided with positive means for moving the actuating clamp upwardly to return it to a new clamping position.

These and other objects of my invention will be apparent from a perusal of the following specification when taken in connection with the accompanying drawings, wherein:

Figure 1 is an elevational view showing a lifting jack constructed in accordance with my invention;

Figure 2 is a partial longitudinal sectional view of the jack of Figure 1, taken on line 2—2 of Figure 3;

Figure 3 is also a sectional view along the line 3—3 of Figure 1;

Figure 4 is a transverse sectional view taken along the line 4—4 of Figure 1;

Figure 5 is a view similar to Figure 2 but showing the actuating clamp in operated position;

Figures 6 and 7 are views showing two modifications of the cross section of the standard; and

Figures 8 to 11 are other modifications of the 5 manner of operating the actuating clamp from the actuating lever.

Referring to the drawings, it will be seen that the present invention is best illustrated as applied to a jack of my pending application, Serial 10 No. 74,969, aforesaid, and comprises a base 10 having an upstanding shaft or standard 11 fixed thereto in any suitable manner, as by means of a pin or the like. The standard 11 carries a lifting body 12 of the jack which is adapted for 15 sliding movement therealong. The lifting body is preferably composed of two metal castings 13 and 14, as best seen in Figure 4. These two castings are preferably secured together at their bottoms by means of screws or rivets 15 which 20 pass through holes in flanges formed at the bottoms of the castings. The body parts are secured together at the top by means of the load engaging saddle 16 which embraces both body parts and which is held against removal from the body 25 by means of a beaded flange 17 formed at the extreme upper portion of the body castings. The saddle is retained against movement downwardly along the body members by means of the flange 18 formed thereon. The saddle is rotatable about 30 the body so that its object or load engaging portion 19 may be readily moved to the desired load engaging position. The load, as illustrated, is a portion B of the bumper of an automotive 35 vehicle, as the lifting jack of the present invention is particularly adapted for use in such connection. As is well known, the bumper is disposed at considerable height above the ground. It is understood, however, that the jack may be applied to other portions of a vehicle or to other 40 types of loads to be raised.

A housing 20 formed at the lower portion of the lifting body carries the actuating clamp 21 and the holding clamp 22 of a jack operating mechanism. As will be seen by reference to 45 Figure 5, the actuating clamp has formed on the upper face thereof a lug 23 adapted for engagement with the body housing when the actuating clamp is in its upper normal position, as shown in Figure 2. A pair of diametrically disposed lugs 50 24 are also formed on the upper face of the actuating clamp to which the lower ends of a pair of springs 25 are secured. The upper ends of these springs are anchored to projections 26 formed on the lifting body members. The op- 55

erating lever 27 for the jack is pivoted by means of a pin 28 to the body members and has an operating portion 29 adapted for engagement with the top of the actuating clamp at a point 5 diametrically spaced from the projection 23. The holding clamp 22 has an extending portion 30 journaled in an opening 31 formed in the housing 20, as best shown in Figure 3. The holding clamp is also formed with a projection 10 32 adapted to extend through an opening 33 formed in the housing diametrically to the opening 31. A compression spring 34 is arranged in a recess 35 formed on the lower side of the projection 32 of the holding clamp 22 and the lower 15 face 35' of the housing 12, whereby said spring normally holds the holding clamp in canted position. The housing 20 also carries an integral outstanding projection 37 which, as best shown in Figure 1, is upwardly and laterally spaced from the projection 32 of the holding clamp. The release bar 36, by which the jack is lowered, is adapted for cooperation on its upper face with the housing lug 37 and on its lower face with the projection 32 of the holding clamp, 20 as will be best understood by reference to Figure 1. Lug 37 forms a fulcrum for this bar.

All of the foregoing construction is shown in my prior application, Serial No. 74,969. The present invention differs therefrom by the provision of interconnecting means between the actuating clamp 21 and the actuating lever 27, which devices are provided with means for positively raising the actuating clamp whether or not the springs 25 are present. It is understood, 30 however, that I prefer to provide my jack with the springs 25 cooperating in connection with the positive means for displacing the actuating clamp 21 as herein about to be described. In the preferred embodiment for carrying out the hereinbefore described function, the actuating clamp 21 is provided with furcations 38 and 39 which receive therebetween a prong 40 made integral with the lever 27, and which prong 40 is disposed below and spaced from the cam surface 29 hereinbefore described. The prong 40 is adapted to fit into the notch formed between the furcations 38 and 39 in the assembly of the jack.

In assembling the jack the two parts 13 and 50 14 of the lifting body 12 are brought into operative juxtaposition with the holding clamp 22 and the actuating clamp 21 arranged within their housing portions. The springs 25, which have been previously secured to the actuating clamp, 55 are connected to the projections 26 on the body parts, and the springs are stretched slightly as the actuating clamp is forced downwardly into the housing portion 20 of the body. With the body parts thus positioned, the screws or rivets 60 15 may be inserted to secure the lower body portions together. The load engaging saddle 16 is then slipped over the upper portions of the body parts into engagement with the flange 18, after which the flange 17 may be beaded over the top 65 of the saddle to secure it in position. The saddle in turn secures the upper portions of the body members together. The compression spring 34 and the operating lever 27 may then be mounted in position, after which, upon compression of 70 the spring 34, the entire movable lifting portion of the jack may be moved downwardly about the standard 11. It will be understood that in thus assembling the device the prong 40 on the actuating lever 27 has been inserted between the furcations 38 and 39 of the actuating clamp 21.

The standard shaft insures that the springs 25 will not slip off of the lugs 26.

In operation, the compression spring 34 normally cant the holding clamp as shown in Figure 3, whereby to cause the biting edges of its central opening to grip the standard 11 and prevent the lifting body 12 from downward movement along the standard. The actuating clamp 21 is held in its normal uncanted and upward position by the springs 25 when such springs are used. As the end of the operating lever 27 is moved upwardly, as indicated by the arrow in Figure 2, its engaging portion 29 causes the actuating clamp 21 to cant whereby to bring the biting edges of its central opening into tight engagement against the standard 11. As the movement of the operating lever is continued as indicated in Figure 5, the actuating clamp acts as a reaction base causing the entire lifting casting to move upwardly along the standard. The holding clamp does not prevent such upward movement, but moves upwardly with the body 12, and by reason of the spring 34 prevents any retrograde movement, thus holding the body in its new upward position. As the operating lever is returned to normal position, the lug 40 positively engages the under side of the furcation 38, thereby positively returning the actuating clamp to upward position. The springs 25 draw the actuating clamp into normal upward uncanted position, thus assisting the positive movement of the connection between the actuating lever 27 and the actuating clamp 21. This positive upward movement of the actuating clamp 21 will overcome any tendency of the clamp to stick due to the presence of rust or dirt on the standard 11, which might otherwise prevent the return of the actuating clamp to uncanted position in the event that the rust or dirt is strong enough to overcome the force of the returning springs 25. The operation may be repeated until the lifting body is brought up to the desired position. Prior to engagement with the load, the entire lifting body may be lifted by hand upwardly along the standard 11, without manipulation of the operating lever 27, the clamps 21 and 22 readily permitting this preliminary adjustment movement. The load engaging saddle member 16 may be readily revolved about the body whereby to bring its load engaging portion 19 into the desired operative position. These features insure speed of jack placement and load raising.

To release the lifting body, the release bar 36 is brought into position as shown in Figure 1 with its upper side in engagement with the housing lug 37 and its lower side in engagement with the projection 32 on the holding clamp. As the right end of the bar 36 is now lowered, the spring 34 will be compressed, allowing the holding clamp to release its grip upon the standard. Downward movement of the lifting body under the load causes a corresponding lowering of the left end of the release bar, and this results in the relief of downward pressure against the projection 32 of the holding clamp. The spring 34 thereupon causes the holding clamp to again grip the standard 11. In other words, the lifting body 12 can be lowered only at the same time that the right end of the release bar is being lowered. If 70 movement of the operating end of the release bar is stopped, the downward movement of the lifting body also immediately stops. By this means the downward movement of the lifting body is under accurate and positive control at all times whereby 75

to insure complete safety as well as ease of operation.

In Figures 6 and 7 of the drawings I have shown different cross sectional shapes of the standard 11.

5 These are shown at 11' and 11" respectively.

Referring to Figures 8 to 11 of the drawings, I have illustrated many different ways of obtaining substantially the same result shown by the mechanism in Figures 1 to 5, inclusive, it of course 10 being obvious that other ways may likewise be used within the scope of the present invention.

In Figure 8 I have shown the actuating clamp 42 as provided with an upstanding lug 44 spaced from the top surface of the actuating lug so as to provide a pocket in which a prong 48 on the actuating lever 46 is adapted to operate, the prong 48 serving to push downwardly on the top surface of the actuating clamp 42 in order to cant the actuating clamp 42. Likewise the prong 48 operates with the tooth or lug 44 for turning the actuating cam in case the cam has a tendency to stick in its clamping action. In this construction the hook or prong 44 will cooperate with the tooth on the handle socket of the actuating lever 46, thereby lifting the actuating cam to its uncanted position at the top of the stroke.

In Figure 9 a similar result is accomplished by means of a link 52 pivotally connected as at 58 to the end portion 60 of the actuating clamp 62. The other end of the link 52 is slotted as at 56 to receive a pin 54 integrally formed or fastened to the actuating clamp 50. In this case the action is substantially the same.

In Figure 10 the link 66 is formed on the actuating clamp 64, being provided with a slot 68 in which a pin 70 on the prong 72 of the actuating lever 74 operates so that when the lever 74 is raised the prong 72 thereof will press downwardly on the top of the actuating clamp 64 to cant the same as hereinbefore described, and then on the return stroke of the actuating lever 74 the lost motion connection will first take place, after which the pin 70 will ride against the upper surface of the slot 68 to lift the actuating clamp 64 to its uncanted position.

A similar result is obtained as shown by the mechanism in Figure 11, wherein the two furcations 80 and 82 of the actuating lever 78 are on opposite sides of the actuating clamp 76. In each of these instances I prefer to use the actuating clamp with the spring means shown in dotted lines, all as hereinbefore described in connection with the operation of Figures 1 to 5, inclusive.

55 It is understood that in some instances the present invention may be adapted to a type of friction grip lifting jack or shore wherein instead of having a lever such as the present lever 21 permanently pivoted to the body 12, the lever is independent thereof and is adapted for insertion through an opening in the housing to engage the actuating clamp. In this type of construction the independent lever is provided with means forming a disconnectable fulcrum point with the body, and obviously will be provided with the cam 29 and the lug 40, which latter lug is positioned between the furcations 38 and 39 on the actuating clamp 21 when the lever is placed in proper actuating position.

70 The claims of this case are directed more particularly to the operative connection between the operating lever and the actuating clamp, and associated structures, other features disclosed but not herein claimed, being claimed in applicant's 75 copending applications, including applications,

Serial No. 43,752, filed October 5, 1935, and Serial No. 74,969, filed April 17, 1936.

It is obvious that various modifications may be made in the specific embodiments of the invention shown for the purpose of illustration. Accordingly the invention is not to be limited to the precise constructions shown and described, but only as indicated in the following claims.

The invention is hereby claimed as follows:

1. In a lifting jack of the friction grip type, an elongated support, a body embracing the support and movable relatively thereto, a holding clamp on the body and embracing the elongated support, said holding clamp being normally canted to prevent relative movement between the body and the elongated support in one direction, release means for uncanting the holding clamp to allow such movement, and an actuating clamp embracing the elongated support and normally uncanted relative to said elongated support, said actuating clamp having furcations, said body having an opening opposite said furcations adapted to receive a lever, said lever having a cam-like portion adapted to engage the actuating clamp whereby to cant the clamp and to cause the relative movement of said body to said support in a direction along said support, said lever also having a lug insertable between the furcations of said actuating clamp whereby on movement of said lever to return the canted actuating clamp to normally uncanted position.

2. In a lifting jack of the friction grip type, an elongated support, a body embracing the support and movable relatively thereto, a holding clamp on the body and embracing the elongated support, said holding clamp being normally canted to prevent relative movement between the body and the elongated support in one direction, release means for uncanting the holding clamp to allow such movement, an actuating clamp embracing the elongated support and normally uncanted relative to said elongated support, said actuating clamp having furcations, said body having an opening opposite said furcations adapted to receive a lever, said lever having a cam-like portion adapted to engage the actuating clamp whereby to cant the clamp and to cause the relative movement of said body to said support in a direction along said support, said lever also having a lug insertable between the furcations of said actuating clamp whereby on movement of said lever to return the canted actuating clamp to normally uncanted position, and spring means for normally urging said actuating clamp to normal uncanted position.

3. In a lifting jack of the friction grip type, an elongated support, a body embracing the support and relatively movable to the support, a holding clamp anchored on the body and embracing the elongated support, said holding clamp being normally canted to prevent relative movement between the body and the elongated support in one direction, release means for uncanting the holding clamp to allow such movement, an actuating clamp embracing the elongated support, means providing a pivot between one portion of said actuating clamp and the body to permit said actuating clamp to pivot relatively to the elongated support to canted and uncanted position relative to said elongated support, spring means normally urging said actuating clamp to normally uncanted position, said actuating clamp having furcations at a point opposite the pivotal portion formed on said actuating clamp, said support having an opening opposite said furca-

tions on said actuating clamp, and an actuating lever adapted to be inserted through said opening, said actuating lever having a portion adapted to engage the actuating clamp to cant the clamp 5 relatively to the elongated support whereby said body may be moved longitudinally of and relatively to the elongated support, and said lever also having a lug adapted to lie between the furcations of said actuating clamp whereby on proper movement of said lever to shift said actuating clamp to uncanted position relatively to said elongated support.

4. In a lifting jack of the friction grip type, an elongated support having a base, a body embracing the support and relatively movable to the support, a holding clamp anchored on the body and embracing the elongated support, said holding clamp being normally canted to prevent relative movement between the body and the elongated support in one direction, release means for uncanting the holding clamp to allow such movement, an actuating clamp embracing the elongated support, said actuating clamp having an upstanding lug disposed on one face thereof and adapted to engage the body at a point lying on a diametral line through the actuating clamp whereby to form a pivot for canting and uncanting movement between the actuating clamp and the body respectively, spring means engaging the actuating clamp at points passing through a diameter of the actuating clamp disposed at right angles to the diametral line on the actuating clamp passing through the aforementioned pivotal lug of the actuating clamp for normally urging the actuating clamp to uncanted position relatively to the body and to the elongated support, said actuating clamp having spaced apart portions disposed in a diametral line passing through the pivotal lug for the actuating clamp, and an 40 actuating lever having a cooperative portion adapted to engage one of said last mentioned portions on the actuating clamp for shifting the actuating clamp to uncanted position and for shifting the body relatively to the elongated support, and having another portion adapted to engage the other last mentioned portion of said actuating clamp for positively returning the actuating clamp to uncanted position.

5. In a lifting jack, a base, an upstanding shaft 50 mounted thereon, a load lifting member, means for frictionally gripping the member to the shaft, said means comprising a pair of frictional clamps, one of which forms a part of means to move the member along the shaft and the other of which is adapted to hold the member against retrograde movement on the shaft, means including a spring and a lever member for controlling said moving clamp, said lever member being pivotally mounted on said load lifting member and having 60 a pair of spaced portions adapted to engage opposite portions of said moving clamp whereby to enable actuation of this clamp by the lever member into gripping and non-gripping positions with respect to the shaft, said lever member being 65 adapted to fulcrum upon the moving clamp to advance the load lifting member along the shaft, a spring urging the holding clamp into gripping engagement, and means for releasing the holding clamp.

70 6. In a lifting jack of the friction grip type, a base, an upstanding shaft mounted thereon, a lifting body slidably mounted on said shaft, a laterally extending load engaging member carried by said lifting body, a holding clamp mounted 75 within said body and embracing the shaft, a

spring for canting said holding clamp whereby to prevent movement of the body downwardly along the shaft, release means for uncanting the holding clamp to permit such movement, an actuating clamp also mounted within the body and embracing the shaft, spring means for controlling the operation of said actuating clamp, and a lever assembly pivoted to the body, said actuating clamp having a radially projecting operating portion, and the lever assembly being provided with a pair of spaced portions adapted to engage the radially projecting operating portion of said actuating clamp on the upper and lower sides thereof whereby to enable the canting and uncanting of the actuating clamp as the lever assembly is pivoted with respect to the lifting body.

7. A lifting jack comprising a base, a load-lifting member operatively supported by the base, and means for moving the load-lifting member relative to the base comprising a housing, a pair of friction clamps associated therewith, and a shaft extending through the housing and the clamps, one of said clamps being an actuating clamp and the other of said clamps being a holding clamp, a spring for holding the holding clamp in canted gripping engagement with the shaft, a spring for holding the actuating clamp in predetermined position with respect to the shaft and for controlling the operations of said actuating clamp, an operating lever pivotally mounted on the housing, said actuating clamp being provided with a pair of spaced projections and the operating lever being provided with a projection adapted to lie between the spaced projections of the actuating clamp and to operatively contact therewith during the pivotal movements of the lever, the operating lever projection being adapted to engage one of the actuating clamp projections to effect the canting of the clamp and the lifting movement of the jack as the operating lever is 40 pivoted in one direction, the actuating clamp spring serving to maintain said operative contact during reverse pivotal movement of the operating lever, and said operating lever projection being adapted to make operating contact with the 45 other clamp projection to effect the uncanting of the clamp in the event of the failure of operation of said spring.

8. A lifting jack comprising a base, a load-lifting member operatively supported by the base, 50 and means for moving the load-lifting member relative to the base comprising a housing, a pair of friction clamps associated therewith, and a shaft extending through the housing and the clamps, one of said clamps being an actuating 55 clamp and the other of said clamps being a holding clamp, a spring for holding the holding clamp in canted gripping engagement with the shaft, a spring for holding the actuating clamp in predetermined position with respect to the shaft and 60 for controlling the operations of said actuating clamp, an operating lever pivotally mounted on the housing, said actuating clamp being provided with a pair of spaced operating surfaces and the operating lever being similarly provided with a 65 pair of spaced operating surfaces adapted to respectively operatively contact with the operating surfaces of the actuating clamp during the pivotal movements of the lever, one of the operating surfaces of the lever being adapted to engage one 70 of the operating surfaces of the actuating clamp to effect the canting of the clamp and the lifting movement of the jack as the operating lever is pivoted in one direction, the actuating clamp spring serving to maintain said operative contact 75

5 during reverse pivotal movement of the operating lever, and the other operating surface of the lever being adapted to make operating contact with the other operating surface of the clamp to effect the uncanting of the clamp in the event of failure of operation of said spring.

9. A lifting jack comprising a base, an upstanding shaft mounted thereon, a load-lifting housing longitudinally slideable on the shaft, and means for moving the load-lifting housing along the shaft comprising a pair of friction clamps associated with the housing and mounted on the shaft, one of said clamps being an actuating clamp and the other of said clamps being a holding clamp, a spring for holding the holding clamp in canted gripping engagement with the shaft, a spring for holding the actuating clamp in predetermined position with respect to the shaft and for controlling the operations of said actuating clamp; an operating lever pivotally mounted on the housing, said actuating clamp being provided with a pair of spaced projections and the operating lever being provided with a projection adapted to lie between the spaced projections of the actuating clamp and to operatively contact therewith during the pivotal movements of the lever, the operating lever projection being adapted to engage one of the actuating clamp projections to effect the canting of the clamp and the lifting movement of the jack as the operating lever is pivoted in one direction, the actuating clamp spring serving to maintain said operative contact during reverse pivotal movement of the operating lever, and said operating lever projection being adapted to make operating contact with the other clamp projection to effect the uncanting of the clamp in the event of the failure of operation of said spring.

40 10. A lifting jack comprising a base, an up-standing shaft mounted thereon, a load-lifting housing longitudinally slideable on the shaft, and means for moving the load-lifting housing along the shaft comprising a pair of friction clamps.

associated with the housing and mounted on the shaft, one of said clamps being an actuating clamp and the other of said clamps being a holding clamp, a spring for holding the holding clamp in canted gripping engagement with the shaft, a spring for holding the actuating clamp in predetermined position with respect to the shaft and for controlling the operations of said actuating clamp, an operating lever pivotally mounted on the housing, said actuating clamp being provided with a pair of spaced operating surfaces and the operating lever being similarly provided with a pair of spaced operating surfaces adapted to respectively operatively contact with the operating surfaces of the actuating clamp during the pivotal movements of the lever, one of the operating surfaces of the lever being adapted to engage one of the operating surfaces of the actuating clamp to effect the canting of the clamp and the lifting movement of the jack as the operating lever is pivoted in one direction, the actuating clamp spring serving to maintain said operative contact during reverse pivotal movement of the operating lever, and the other operating surface of the lever being adapted to make operating contact with the other operating surface of the clamp to effect the uncanting of the clamp in the event of failure of operation of said spring.

11. A lifting jack as defined in claim 8 wherein the spaced operating surfaces of the operating lever are provided respectively on spaced operating members associated with the operating lever. 30

12. A lifting jack as defined in claim 10 where-
in the spaced operating surfaces of the operat- 35
ing lever are provided respectively on spaced op-
erating members associated with the operating
lever.

13. A lifting jack as defined in claim 8 where-
in the spaced operating surfaces of the actuating
clamp are provided on a projection extending
radially from the body of the actuating clamp. 40

MILLARD B. LUCKER.
